UNITED STATES PATENT OFFICE.

RAYMOND A. WILLIAMS, OF PITTSFIELD, MASSACHUSETTS.

INSULATED-WIRE STRIPPING AND SCRAPING DEVICE.

Application filed December 11, 1924. Serial No. 755,300.

To all whom it may concern:

Be it known that I, RAYMOND A. WILLIAMS, a citizen of the United States, residing at Pittsfield, in the county of Berkshire and the State of Massachusetts, have invented a certain new and useful Improvement in an Insulated-Wire Stripping and Scraping Device, of which the following is a specification.

10 My invention relates to improvements in that class of devices adapted for stripping insulation from insulated wire, and also for scraping the wire after the insulation has been removed.

15 Another object of my device is to provide means whereby the length of the wire to be stripped may be regulated to any desired length. This object I accomplish by providing a tubular device with an internal regulating guide.

20 Referring to the accompanying drawing, in which like numerals indicate like parts, Figure 1 is a plan view showing the combined stripping jaws and the wire scraper. Figure 25 2 is a front elevation view in part section showing the details of construction more clearly in accordance with my invention. Figure 3 is a side elevation view of the device.

30 In the drawing, the numerals 1 and 2 designate the pivoted members of the tool which are connected by means of the pivot pin 16. The upper part of the tool is provided with stripping jaws 3 and 4, and the 35 jaws are secured to the pivoted members by means of screws 5. The stripping jaw 3 is serrated on the outer end and operates in conjunction with the wire scraper 18.

40 A U-shaped wire scraper 18 is pivoted to one of the pivoted members of the tool by means of a pin 19, and is held in contact with the serrated stripping jaw 3 by means of springs 21, which are secured to one of the pivoted members of the tool and to the wire 45 scraper by means of the pins 20. It will be seen by referring to the drawing that the wire scraper is serrated, and by means of the springs 21 the opening 22 between the serrated edges of the stripping jaw 3 and the 50 wire scraper 18 may be regulated to take various sizes of wire.

A tubular member 6 passes thru the pivot pin 16 and is secured thereto, and the said tubular member is provided with notches 7 on one side. A tubular member 23 is placed over the tubular member 7 and the said

tubular member 23 is provided with a recess 24 on the side adjacent to the notched tubular member 6. A spring clip 12 is attached to the tubular member 23, and the lower end of the spring clip passes thru the recess 24 and is held in contact with the notched tubular member 7 as indicated at 13, by means of the resiliency of the clip. The tubular member 23 is free to slide up and down over the tubular member 6. The tubular member 6 is provided with a recess 9, to provide means for regulating the guide 8 to pass up and down within the tube. The guide 8 is provided with an extension rod 10 which rod is held in contact with the tubular member 23 by means of a pin 11.

The insulated wire 17 is placed between the stripping jaws 3 and 4 and into the tubular member 6 and in contact with the guide 8. By operating the guide 8, by means of the tubular member 23 and the spring clip 12, which clip engages in the notches 7, any desired length of insulated wire may be stripped by regulating the guide 8 within the tubular member 6 to the desired length required. By means of the springs 21 the serrated edges of the stripping jaw and the wire scraper are held in close contact, thereby assuring the proper tension between the serrated edges of the stripping jaw and the wire scraper, to regulate the opening 22 to conform to various sizes of wire to be scraped.

55 The lower end of one of the pivoted members of the tool is provided with an eccentric disk 14, which disk is pivoted to the tool member 1 by means of a pin 15. The eccentric disk is so designed, that by placing one of the flat surfaces of the disk on the tool member adjacent, the stripping jaws are regulated to cut thru the insulation on the wire without injuring the wire. Various sizes of wire may be stripped by regulating the flat surfaces on the eccentric disk in an eccentric manner from the pivot pin 15.

60 It is obvious that changes might be made in various more or less substantially different forms without departure from the spirit of my invention, therefore I do not wish to limit myself to the exact construction.

Having thus described my invention, what I claim is:—

65 1. The combination with a pivoted tool member of the class described having operating handles and comprising stripping jaws, means to secure said jaws to the tool

members, a tubular member for regulating the length of the cable to be stripped, a stop within said tubular member, and an extension rod affixed to said stop, said tubular member provided with a plurality of notches on the outer side, a spring clip slidably affixed to the said tubular member and cooperating with the notches thereon, and an eccentric cam rotatably connected to the tool member to provide means to regulate the size of the wire to be stripped.

2. The combination with a pivoted tool member of the class described comprising stripping jaws, means to secure said jaws to the tool members, a tubular member for

regulating the length of cable to be stripped, said tubular member provided with a longitudinal slot, and the outer side of said tubular member provided with a plurality of notches, a stop within said tubular member, an extension rod affixed to said stop, means to operate said stop, a tubular member provided with a spring clip, said clip to cooperate with the notched tubular member, and an eccentric cam rotatably connected to the tool member to provide means to regulate the size of the wire to be stripped.

In testimony whereof I set my hand and signature.

RAYMOND A. WILLIAMS.
